METHOD OF RECORDING CUTTING OPERATIONS PERFORMED UPON SHEET MATERIAL

Albert L. McMaster, Lynn, Mass., assignor to
 Krippendorf Kalkulator Company, Portland,
 Maine, a corporation of Maine

Application August 6, 1930, Serial No. 473,487

5 Claims. (Cl. 33—6)

This invention relates to a method of recording cutting operations performed upon sheet material and is herein illustrated as applied to the recording of operations performed upon hides or skins in producing blanks such as blanks for shoe uppers.

It is an object of the invention to record cutting operations performed upon sheet material in such a way that workers may be readily instructed in planning and performing cutting operations upon sheet material and conveniently for checking the effectiveness of such operations after the work has been completed.

To this end, and as illustrated, the method 15 contemplates the marking of sheet material to indicate the location according to a definite scheme of different areas of the sheet material and, after the cutting, assembling the cut pieces and the scrap upon a chart by the aid of the 20 markings. Preferably, the markings are placed upon the back of the material so that, as in the case of operating upon leather to produce shoe part blanks, their removal will not be necessary, the cutting operations are performed in the usual 25 manner, and the cut pieces are numbered in sequence so that the plan followed in making the cuts can later be studied. In the assembling, the cut pieces and scrap are preferably secured backs 30 uppermost to a chart having markings corresponding to those upon the material, and a backing is secured to the scrap after which the assembly is inverted, the cut pieces are removed, the spaces remaining are designated by corresponding sequence marks, and marks are placed 35 upon the backing and scrap to divide the entire area into smaller areas which may represent portions of material of different quality. By the use of such procedure the cut pieces can be readily assembled to form a record by which the effectiveness of the cutting operations can be studied.

Thus it is possible, for example, to effect economies in the cutting of leather and to make suitable selection of the various grades of leather in a skin for the parts of shoe uppers to which they 45 are best suited. In this connection, in the resulting record the location of the spaces, from which the cut pieces were removed, relatively to different areas of a skin will be readily observable with the result that the efficiency of the 50 operator in cutting the pieces in areas in which the quality of the skin is suitable for the use for which each piece is intended, can be ascertained. Also, since the effectiveness of the cuts made, from the standpoint of economy of material, depends, to a large extent, upon the order followed

in cutting pieces of various shapes from the different areas of a skin, the record of the sequence of cutting operations provides a check upon the effectiveness of the planning of the operator. By the study of such records operators can be instructed how best to plan and perform the cutting operations in such manner as to obtain the greatest possible value in usable pieces from a skin.

The invention will best be understood by reference to the following description when taken in connection with the accompanying drawings illustrative of the method and means, while its scope will be pointed out more particularly in the appended claims.

In the drawings:

Fig. 1 is a plan of a stencil and a skin, the former being superimposed upon the back of the latter in the step of marking the skin in carrying out the method;

Fig. 2 is a plan illustrating a portion of Fig. 1 on an enlarged scale to show the perforations in the stencil at a sufficient size to make them appear as perforations, which is impossible at the small scale of Fig. 1;

Fig. 3 is a plan of the face of the skin illustrating the step of applying the patterns to the skin and showing the sequence of pattern application;

Fig. 4 is a plan illustrating the step of assembling the leather blanks and the scrap and corresponding paper blanks and securing them to a chart having markings thereon corresponding with and made by the aid of the stencil;

Fig. 5 is a plan illustrating the steps of securing the paper blanks to one another by the use of small gummed strips and of applying large gummed strips over the entire area of the assembled blanks and scrap to unite them so that they may be handled as a sheet and inverted; and

Fig. 6 is a plan of the assembly inverted with the backs of the blanks exposed and with the chart removed illustrating the step of trimming away the surplus paper to the outline of the skin.

Referring to the drawings and to the method of and means for practicing the method illustrated therein and having reference at first more particularly to Fig. 1, there is shown as a part of the apparatus suitable printing means, herein a 105 stencil 10 comprising a sheet of appropriate material such as heavy wax-impregnated paper or perhaps celluloid which is provided with perforations whose characteristics and arrangement are such that a plurality of areas may readily

be distinguished from one another as to their location with relation to the other areas and to the entire area according to a predetermined plan by merely noting the character and arrangement of the perforations.

It is well known that the density and other characteristics of a skin vary in accordance with the relation of each part of the skin to the anatomy of the animal from which it is taken. It is, therefore, desirable and customary to make cuts for an upper from the areas which are best suited to the particular part of the boot or shoe in which the cut is to be used. For practical purposes it may be considered that a skin comprises nine areas which should be borne in mind in making the cuts. In accordance with my invention, these areas are designated by certain arbitrary markings, herein the numerals 1 to 9 inclusive, the numeral 1 designating the left hind leg, 2 the right hind leg, 3 the left front leg, 4 the right front leg, 5 the head, 6 the butt, 7 the left flank, 8 the right flank and 9 the center, these areas being considered with reference to the front or face of the skin.

These areas are defined by two parallel broken lines 11, which may properly be called longitudinal lines because they extend longitudinally of the skin when the stencil is superimposed upon the latter, and there are two parallel transverse broken lines 12 perpendicular to the longitudinal lines. As it is important that the stencil shall be centered with relation to the "back bone" of the skin, the stencil is provided with a fifth broken line 13 which is a longitudinal center line midway between the two longitudinal lines 11. Instead of making lines 11, 12 and 13 as continuous lines drawn or printed upon the stencil, each is of the nature of a broken line formed by a series of perforations. For example, as shown, each of the longitudinal lines 11 comprises a series of numerals 1, each of the transverse lines 12 comprises also a series of numerals 1 and the longitudinal center line comprises a series of small circles. These numerals and circles are perforations.

Each of these areas or sections is identified by certain arbitrary markings which at once indicate not only the arbitrary number of the section as above alluded to but also the relation of each section to the lines 11, 12 and 13, it being remembered that the two lines 11 and the two lines 12 define the boundaries of the sections. Taking, for example, the section 1 which is the left hind leg (appearing in Fig. 1 at the right because it is the back of the skin which is to be stenciled), the designation 11A is the start of the numbering or marking for that particular section and these markings read from the upper left hand corner of the section downwardly as 12A, 13A down to 16A and then a second column starts at the top of the section with the mark 11B and so on. Thus the added symbol A indicates the first column, B indicates the second column and so on. The mark A in any section is the nearer to the "back bone", that is to say, the longitudinal section line. In section 1 the second numerals of the several vertical rows run from the transverse line downwardly, while the letters read outwardly with reference to the center of the skin.

In addition, there are rows of the numeral 1, or whatever numeral may be desired, meaning stencil #1 or whatever number it may bear, and with each of these numerals there is associated an arbitrary symbol meaning that the section

in question is a leg. This same symbol is used on each of the four legs and in the present example this symbol is a square. This disposes of the four sections numbered respectively 1, 2, 3 and 4 which are the leg sections.

Section 5, which is the neck section, is represented by a symbol, herein a diamond. Section 6, which is the butt section, is represented by a symbol, herein a small circle. Section 7, which is the left flank (appearing at the right on the back of the skin), is represented by a symbol, herein a triangle having an apex pointing toward the center of the skin. This is not vital, but helps to locate the section with reference to the center line or "back bone". Section 8, which is the right flank (appearing on the left side of the back of the skin) is also represented by a triangle whose apex points toward the longitudinal center line or back bone of the skin. Section 9, which is the center of the skin, is represented by a large circle, substantially larger in fact than the hereinbefore described small circles which are used elsewhere. It should be understood that all of the described markings are perforations and that in the case of some of the numerals and letters the usual method employed in connection with cutting stencils is used, namely, leaving some of the material to support a part of the numeral or letter which otherwise would be cut out and removed entirely in doing the perforating.

Referring to section 2, which is at the lower left hand corner of the stencil, it will be observed that the readings are downwardly from the lower transverse line 12 and outwardly (toward the left) from the left hand longitudinal line 11. For example, the first marking is 21A, the second in the same column 22A, the third 23A and so on down to 26A. The second column reads 21B, 22B and so on down to 26B. Referring to section 3, which is at the upper right hand corner of the stencil, the markings read upwardly and outwardly (toward the right), that is to say, they begin at the lower left hand corner of this section above the upper transverse line 12 and read in an upward direction 31A, 32A, 33A and so on 120 to 38A. The next column reads upwardly from 31B to 38B, and the remaining columns follow in succession from left to right. In section 4, which is at the upper left hand corner of the stencil, the readings commence at the lower right hand corner of said section with 41A, reading upwardly 42A, 43A to 48A. The next column begins 41B and ends 48B. The remaining columns are read in succession from right to left.

The section 5 is divided into two left and right sections on either side of the longitudinal center line 13. In the right hand one of these two sections the readings begin at the lower left hand corner and read upwardly 51A, 52A, 53A to 58A. The next column at the right begins with 51B 135 and ends with 58B. The remaining columns in succession from left to right are read in the same manner. Going back now to the longitudinal center line and considering the left hand division of section 5, the readings commence with A51 and 140 read upwardly to A58, the "A" being placed before the 5 to indicate that it is the left hand division of the section as contrasted with the right hand division of the section in which the letter is at the end of the marking instead of at the 145 beginning. The remaining columns are read successively from right to left and upwardly.

Section 6, which is at the lower center, likewise is divided by the longitudinal center line 13 into two left and right sections. The readings in the 150

right hand division begin with 61A and read downwardly to 66A, the next column begins 61B and ends 66B and the remaining columns read successively from left to right to and including the column which begins 61E and ends with 66E. The left hand portion of this section begins with the column A61 and ends with A66, and the columns read successively from right to left ending with the column beginning E61 and ending E66.

10 In the section 7, the readings commence at the lower left hand corner with the first column reading upwardly from 71A to 78A and the successive columns read from left to right ending with the column which begins 71F and ends 78F. In the corresponding section 8, which is at the left hand side of the stencil, the readings begin at the lower right hand corner with 81A with the first column reading upwardly to 88A and the successive columns are read from right to left to the last column which begins with 81F and ends with 88F.

Section 9, which is at the central portion of the stencil, is divided by the longitudinal center line 13 into two portions at the right and left respectively of the center line. In the right hand portion the readings commence with 91A in the first column reading upwardly to 98A, and the columns read successively from left to right to and including the column which begins 91E and ends with 98E. In the left hand portion of this section, the readings begin at the lower right hand corner with A91 reading upwardly to A98 and the columns read in succession from right to left to and including the column which begins E91 and ends with E98.

35 The described plan of marking is such that the user can with a little practice readily identify the location of any blank or piece of scrap on the hide marked by the aid of the stencil, with reference to other adjacent areas and with reference to the entire area. The same is true of the second piece of apparatus, which is a chart 14 of suitable material such as heavy paper or cardboard and having markings corresponding with those of the stencil and conveniently made by 40 the aid of the latter by superimposing one upon the other and dabbing ink or the like through the perforations onto the paper.

The first step in carrying out the method is to lay the stencil on the back or flesh side of a skin 50 15 (see Fig. 1) and stencil the skin by the use of a brush through the perforations in the stencil. In Fig. 1 a portion of the stencil is broken away to expose a portion of the skin and to show the markings on the latter. The next step is to place 55 the skin face up and to commence to make the cuts. As a part of this step a person standing beside the cutter takes the cut pieces or blanks one by one in the order in which they have been cut by the cutter and marks them with suitable 60 symbols such as numerals (see Fig. 3) indicating the sequence of the cuts. These marks are made upon the front or back of each blank. In the present example, they are made on the front and may be erased later. If they are made on the back, 65 they need not be erased. The cutter is given general instructions as to the best sequence, but the sequence will vary somewhat with different skins and with different individuals. An important thing is to have the second person standing by 70 to number the cuts as they are made. By this means, when the blanks and the scrap are later reassembled, the sequence in which the cuts were made can be shown, an analysis of the pattern application can be made and corrective suggestions can be made to the cutter.

The next step is for the supervisor or inspector to assemble the blank on the paper chart (see Fig. 4) and to secure them one by one to the chart as by the use of thumb tacks 16. The scrap is then laid on and fitted in between the blanks. The faces of the pieces are placed against the chart and in Fig. 4 the numerals indicating the sequence of the cuts appear in dotted lines inverted.

80 The next step is to cut out of paper a full set of cut-outs or blanks 17 corresponding to the leather cut-outs and to lay each paper cut-out upon the leather cut-out of which it is a counterpart. As a part of this step, the individual paper cut-outs 17 are fastened to the adjacent scraps 18 (see Fig. 5) by small pieces of gummed paper tape 19. These are very numerous and are placed in such a way as to secure the parts together to avoid their becoming shifted accidentally.

85 The next step is to cover the entire area with a backing of gummed strips 20 laid edge to edge (see the right hand portion of Fig. 5). In practice these strips may be approximately four inches wide. I prefer to use these strips instead of a single sheet because of the greater convenience of application. These strips will adhere to the paper cut-outs and to the scrap. The paper cut-outs thus protect the faces of the cuts.

90 The next step is to invert the entire assembly by laying a board or cardboard on top of the assembly as it appears in Fig. 5 and then turning the board and the assembly bottom side up as a unit. The reassembling chart 14 is then removed carefully from the points of the thumb tacks. The leather blanks are then picked out 100 readily because they are not stuck to the paper cut-outs beneath them. In other words, the paper cut-outs serve to prevent the leather blank from being damaged by the gummed paper. Each leather cut has, of course, the previously applied 105 number indicating the sequence in which it was cut and, as the leather blanks are removed one by one, the inspector marks the sequence numbers upon the paper cut-outs in the spaces from which the leather blanks were taken (see Fig. 6). 110

115 Finally the gummed paper about the edge of the skin is trimmed away to the outline of the latter. The commencement of this operation is indicated at the right hand portion of Fig. 6. When this has been completed, division lines corresponding with the lines 11, 12 and 13 and the 120 numbers of the sections (1 to 9 inclusive) are marked by suitable means such as a pencil or otherwise, partly on the scrap and partly on the paper in the cut out places. The resulting record, 130 which tells the story of what was done by the cutter, can be given a filing number by means of a sticker or otherwise indicating the number of that particular skin.

135 The cutter himself has no part in all of this except to follow the general instructions and to perform the cutting operation just as if his work were not being subjected to observation. Except for the actual cutting operation, the other steps are taken by one or more other persons. The 140 described method enables definite corrective instructions to be given to the cutter. If, for example, the first cut was made in section 1 (the left hind leg), the second cut in section 2 (the 145 right hind leg), the third cut in section 3 (the left front leg), and the fourth cut in section 4 (the right front leg), the method used in making these first four cuts is definitely established. It would thus be possible by testing cuttings to prove whether it would have been better judgment to 150

have made all of these first four cuts in section 5 (the head) as shown in the drawings or to have made, in certain types of skins, a start in some other section. In addition to noting how a cutter 5 starts a skin, it is also important to check how he finished, that is to say, in what section his last cut was made. In the drawings, it appears that the last cut numbered 56 was made in section 9.

The sequence of cutting shown in the drawings 10 is what is called "skirting" the skin, the cuts all being made to clean up all of the poorer or doubtful leather as regards stretch, poor quality, etc., first. This leaves the center of the skin (sections 15 9 and 6), which contains the best grade leather, to be cut last into vamps or tips, which parts of the shoe should be cut from the best quality in each skin. It should here be noted that this piece of stock left for this purpose is of generally 20 square shape and enables the cutter to apply his patterns closely with regard to pattern shape only, taking advantage of all curves and angles in fitting the patterns together without having the added disadvantage of being obliged to consider the stretch of the leather and other considerations which he would have had to bear in 25 mind if these sections 6 and 9 had been cut first and if consequently he had been obliged to finish the cutting in any other irregularly shaped section. Another advantage is found in cutting 30 colored leather, because this brings into the situation another factor inasmuch as all colored shoes are "paired up", that is to say, all of the parts which go to make up a pair of shoes (as vamps, quarters, tips, etc.) are mated as closely 35 as possible to the same shade of color. As most colored leather varies in shade in different parts of the same skin, it is a distinct advantage to be able to trace the sequence of the cuts as made, because, in cutting up a colored skin, the proper 40 method or sequence of cuts might and probably would be entirely different from that used for cutting up a black skin of the same general size and shape.

Another advantage is that in cutting side 45 leather (which is a large skin of cowhide or horse-hide cut in halves down the backbone), it is often possible in a large piece of leather to obtain what is called a "run" or combination of cuts one after the other in which advantage is taken of the pattern shape to fit the patterns together closely, thereby reducing the waste or scrap between the cuts to a minimum. Establishing a "run" and holding it depends to a great extent on the way in which it was started. Having the 50 cuts of a "run" numbered as made is vital in giving instructions for its use. This "run" advantage also applies to cutting cloth or other materials in which the question of quality (i. e., imperfections in skins, stretch, etc.) would not be a factor, the cutter's whole problem here being one of close patterning with a clear field in which to work.

Another advantage is found in a course of 55 instructions wherein it would be necessary to cut partly into two or more skins to illustrate properly the method to be used. For example, to cut up properly a certain type of kid skin, the head or section 5 cuts are made first. The two front leg cuts, sections 3 and 4, are made next. The second hind leg cuts, sections 1 and 2, are next made and so on until the cutting of the skin is completed.

Two or more ways of numbering the cuts could be employed. The first and simplest is to use 60 one skin and to number the cuts in the manner

which has already been described. Another way is to make the first two head cuts in one skin, reassemble that skin with these two cuts only having been made and then taking the second skin and making the same two head cuts and in addition two front leg cuts, after which the second skin is reassembled. Then a third skin is taken, and the two head cuts and the two front leg cuts as well as the two hind leg cuts are made. This plan might continue until five or six skins had been used to show the progress through the skins.

Two ways of numbering these cuts might be employed. The first would be to start with number 1 in the first skin and to number the first two cuts numbers 1 and 2. On the second skin the four cuts are numbered 1 to 4 inclusive, that is to say, the numbers 1 and 2 used on the first skin are used again in section 5 or the head section. Cuts are made as in the first skin and numbered 1 and 2, but in addition the numbers 3 and 4 are used. In the third skin, the numbers 1 to 4 inclusive are used as on the second skin and the added numbers 5 and 6 are used. This numbering method is followed on all of the skins used to illustrate this method of numbering. Following this numbering method it would be necessary to give each skin a number to show where the first cuts numbered 1 and 2 originated.

The second way of numbering when two or 105 more skins are used would be to start in the first skin with cuts 1 and 2, then go to the second skin, numbering the cuts 3 to 6 inclusive, then to the third skin, numbering the cuts 7 to 12 inclusive and so on until the illustration is completed.

The foregoing method establishes a shoe quality standard. In shoe making an attempt is always made to obtain what is called a uniform upper, that is to say, a pair of shoes is so matched that the corresponding parts of the same pair 115 come from corresponding parts of the skin, that is, the leg cuts together, the head cuts together, flank cuts together and so on.

In a pair of shoes requiring four quarters or tops, having three of them cut from the leg sections and the fourth from a flank section would be called mis-mating. While this has often happened heretofore and they are allowed to go mis-mated and in the cheaper grade of shoes sometimes no attempt is made to mate them, it is also 120 often desirable from a standpoint of quality in shoe making to be sure to have them mated as nearly correctly as possible. Instead of relying on the judgment of a leather sorter as heretofore, it is now possible by the use of my new method 125 to recognize parts of different quality by the markings on the same. By the use of the different symbols, as squares on the leg sections, diamonds on the head section, triangles on the flank sections, etc., it is now a simple matter to separate the cut shoe parts as regards quality.

Two or more parts cut from the same quality section might vary in their value. This variation could be caused by the pattern not being properly placed as regards stretch. Stretch being the natural give or looseness in certain parts of an animal hide, it is of the utmost importance that this factor should be given careful consideration by the cutter in placing his patterns, for in the construction of a quality shoe, stretch or give 140 should be in the right direction.

Another factor to be considered even in the same quality sections is that of having the quarters or tops "toed" into the center of the skin. This is especially important in cutting colored leather be- 150

cause in colored leather the tendency is for the skirts or skin edges to be of a darker shade than the center and this "toeing in" of quarters would mean that the fore part of a quarter would blend better with the vamps. This would constitute another point in quality shoe making. Both of these points can be checked definitely by the use of the described method.

The described method also enables one cut, hide or skin to be identified or distinguished from another. By placing a distinguishing mark on each skin, all parts of one skin can be identified and distinguished from all parts of another skin after the skins have been cut up.

15 It is often desirable when making test cuttings of new leather (as regards quality, etc.) or when testing a cutter's ability (in regard to pattern application) to chart or stencil each skin with a different color or to use some other distinguishing marking. A series of the described stencils with a stencil number included in the design is one convenient method of obtaining this result.

Leather is given to a cutter in jobs. A job consists of a definite number of skins, each skin containing a definite number of square feet from which he is supposed to cut a definite number of shoes or parts of shoes, the allowance or estimated footage necessary for these shoes having previously been determined by surveys of the pattern to be used which may vary according to the size, shape or style of shoe to be cut. The type of skins to be used and the grade and quality of the same also must be considered. A job might contain one skin or fifty, according to size. As a cutter works along, he keeps all cut parts together by size, width, etc., on his bench. All scrap or waste leather which he has been unable to work into the shoe parts, either because of poor quality leather or because of poor judgment in pattern application (not fitting the patterns closely), is thrown into the scrap box under the work bench. Should a job cut "high" (that is, lose a large percentage of leather over the estimated footage allowance), it might be desirable to reassemble every skin cut to determine the reason for this loss.

By having marked the skins differently as previously described, before the job was cut, it would be possible to assort all of the cut shoe parts and scrap pieces from the scrap box and reassemble any desired skin. Another advantage would be found in making test cuttings of a new purchase of leather because it is often desirable to have the leather salesman select what he considers to be an average skin from the lot to be bought.

In addition to this average skin, one might be selected to represent the best and another the poorest, as leather quality varies in different skins of the same grade and price. Should these three selections be made, it would be necessary that each skin should be marked in some way different from the others so that the cut parts and the scrap of one skin could be distinguished from the cut parts and the scrap of the others after the three skins have been cut together in the same job. This desirable result likewise can be obtained by the use of the described method.

Having thus described one method exemplifying the invention, but without limiting myself thereto, what I claim and by Letters Patent desire to secure is:

1. The method of making a record of the location and sequence of cuts in cutting a sheet, comprising placing on various parts of the sheet on

one face thereof marks which indicate their locations according to a definite scheme, cutting blanks from the sheet with the other face uppermost, marking the blanks to indicate the sequence of the cutting, assembling the blanks and scrap upon a chart by the aid of said marks, securing a backing of sheet material to the scrap, inverting the assembly, removing the blanks bearing the sequence marks, and designating by corresponding sequence marks the spaces from which such pieces were removed. 80

2. The method of making a record of the location and sequence of cuts in cutting a sheet, comprising placing on various parts of the sheet on one face thereof marks which indicate their locations according to a definite scheme, cutting pieces from the sheet with the other face uppermost, marking desired pieces to indicate the sequence of the cutting, assembling the desired pieces and scrap upon a chart by the aid of said marks, securing to the scrap a backing of sheet material, inverting the assembly, removing the pieces bearing the sequence marks, designating by corresponding sequence marks the spaces from which said pieces were removed, and placing upon 100 said backing of sheet material and on the scrap marks dividing the entire area into smaller areas. 95

3. The method of making a record of the location and sequence of cuts in cutting a sheet, comprising placing on various parts of the sheet on one face thereof marks which indicate their locations according to a definite scheme, cutting the sheet with the other face uppermost, marking the desired pieces as distinguished from the undesired pieces or scrap to indicate the sequence 110 of the cutting, cutting a set of pieces of paper or the like as duplicates of said desired pieces, assembling said desired pieces with their paper duplicates upon a chart by the aid of said marks and with said desired pieces between said paper 115 duplicates and said chart, securing said paper duplicates to one another by the aid of sheet material adhering thereto, inverting the assembly, removing said desired pieces bearing the sequence marks, and placing corresponding sequence marks 120 upon said paper duplicates.

4. The method of making a record of the location and sequence of cuts in cutting a sheet, comprising placing on various parts of the sheet on one face thereof marks which indicate their 125 locations according to a definite scheme, cutting the sheet with the other face uppermost, marking the desired pieces as distinguished from the undesired pieces or scrap to indicate the sequence of the cutting, cutting a set of pieces of paper or 130 the like as duplicates of said desired pieces, assembling the scrap and said desired pieces with their paper duplicates upon a chart by the aid of said marks and with said desired pieces between said paper duplicates and said chart by removable fasteners, securing said paper duplicates to one another by the aid of sheet material adhering thereto, inverting the assembly, unfastening said second sheet from said desired 135 pieces which were secured to it by said removable fasteners, removing said desired pieces bearing the sequence marks, placing corresponding sequence marks upon said paper duplicates, and placing upon said paper duplicates and upon 140 said undesired pieces or scrap marks dividing the entire area into smaller areas corresponding with said locations according to said scheme.

5. The method of making a record of the location and sequence of cuts in cutting a sheet, 150

comprising placing on various parts of the sheet on one face thereof marks which indicate their locations according to a definite scheme, cutting the sheet with the other face uppermost, marking the desired pieces as distinguished from the undesired pieces or scrap to indicate the sequence of the cutting, cutting a set of pieces of paper or the like as duplicates of said desired pieces, assembling the scrap and said desired pieces with their paper duplicates upon a chart by the aid of said marks and with said desired pieces between said paper duplicates and said second sheet, securing said desired pieces to said chart by removable fasteners, securing said paper dupli-

15

cates to one another by the aid of sheet material adhering thereto, inverting the assembly, unfastening said chart from said desired pieces which were secured to it by said removable fasteners, removing said desired pieces bearing the sequence marks, placing corresponding sequence marks upon said paper duplicates, and placing upon said paper duplicates and upon said undesired pieces or scrap marks dividing the entire area into smaller areas corresponding with said locations according to said scheme, and marks distinguishing said areas from one another and corresponding with the first-mentioned marks.
